UNITED STATES PATENT OFFICE

CHARLES BURROWS, OF BLACKHEATH, LONDON, ENGLAND

LAUNDRY WASHING MACHINE

Application filed May 2, 1930, Serial No. 449,325, and in Great Britain May 14, 1929.

The object of this invention is to provide a simple, convenient and efficient laundry machine suitable for washing collars, cuffs and other small articles.

According to the invention the improved machine comprises a brush or other appropriate rubbing member mounted to rotate over a suitable work-supporting table, means for delivering water and soap or other cleansing agent to said brush, and means whereby the work-supporting table can be moved towards the said rotary brush or rubbing member.

The work-supporting table is arranged to slide relatively to the rotary brush or rubbing member in order that by moving the said table the entire surface of an article laid thereon can be subjected to the action of the rotary brush or rubbing member. Conveniently, the table is pressed by spring pressure away from the rubbing member or brush, and with advantage the said spring pressure is adjustable.

Figs. 1, 2 and 3 of the accompanying illustrative drawings show a machine embodying the invention in front elevation, side elevation, and plan, respectively.

Fig. 4 is a sectional and elevation of the work-supporting table and of the guides in which it slides.

Fig. 5 is a transverse section through the work table showing the rollers on which it works.

The machine comprises a rectangular or other shaped tank 1 mounted on legs 2 and fitted with a steam heating pipe 3 and a drain pipe 5. Sliding through a suitable gland 6 fixed to the bottom of the tank is a vertical rod 7 the lower end of which is connected by a link 8 to one end of a treadle lever 9 on a shaft 10 mounted in bearings carried by cross members 11 fixed to the supporting legs 2. The upper end of the sliding rod 7 is pivoted to a bracket 12 depending downwardly from a platform or frame 13 formed with longitudinal guide ways 14 in which can slide longitudinal runners 15 that are fixed to the underside of a work-supporting table 16 arranged to slide to and fro on rollers 17 mounted on pins 17^a

carried in lugs 13^b downwardly depending from the platform or frame 13, see Fig. 5. The platform or frame 13 with the work table 16 can be moved upwardly towards a rotary scrubbing brush 18 by pressing down the end of the treadle lever 9. Helical springs 19 mounted in cylindrical pockets 20 carried by fixed brackets 21, normally maintain the platform or frame 13 with the work table 16 in a lowered position, the said springs 19 being mounted on screws 22 extending axially through the cylindrical sockets 20. The said screws 22, see Fig. 4, are screwed into the underside of the platform or frame 13, one near each corner thereof, and the springs 19 each bear at one end on a sleeve nut 19^a mounted on the corresponding screw and on a shoulder 20^a of the corresponding cylindrical pocket 20. The pressure of the springs 19 can be adjusted readily by manipulation of the sleeve nuts 19^a. 22^a indicate lock nuts that are tightened up against the sleeve nuts 19^a after adjustment.

The scrubbing brush 18 is removably mounted on a spindle 23 preferably made of rustless steel, that rotates in bearings 24 carried by a fixed bracket 25. The machine illustrated is belt driven and for this purpose the spindle 23 has mounted on it a fixed pulley 26 and a loose pulley 27. Belt shifting arms 28 carried by a sliding bar 29 are provided as usual in belt driven machines. The brackets 21 and 25 are mounted on a supporting base 30 carried on the top of the tank 1 at the rear thereof.

A metal hood 31 encloses the upper part of the rotary brush 18 and soap and water or other cleansing agent is fed to the brush, through funnels 32 fixed to the said hood, by means of taps 33 connected by piping 34 to the delivery side of a rotary pump 35 which draws the liquid from the tank 1 through a suction nozzle 36.

The pump 35 is driven from the spindle 23 by a belt on the belt pulleys 37.

At each end of the tank 1 is a curved upstanding splash guard 38 the upper ends of which may be stayed as by rods 39 connected to the piping 34 as shown. The curvature 103

of the splash guards is such as to lead the liquid splashed thereon back to the tank 1.

The work-supporting table 16 is furnished with a handle 40 at the side and projecting from the top of the table is a stud 41 which 5 may be engaged by the button hole of a collar or cuff being washed.

42 indicates a splash gutter fixed to the front edge of the tank 1 and draining into 10 the tank by means of a pipe 43. 44 indicates a smaller splash gutter that also constitutes a guide rail fixed to the front edge of the treadle-operated rising and falling platform 13. 45 are stops that may be fixed to the 15 sliding work table to limit the sliding movement thereof if desired.

In operation the brush 18 rotates and a supply of hot soapy water is constantly fed thereto by means of the pump 35 through 20 the piping 34 and taps 33 during such rotation. The platform of frame 13 with the work table 16 normally tends to assume its lower position by its own weight assisted by the springs 19 so that there is ample clearance 25 to place an article such as a collar or cuff thereon below the brush 18. The platform or frame 13 with the work table 16 are then raised by operation of the treadle 9 so that the article is pressed against the rotating brush 18. The work table 16 is then moved to and fro in the guides 14 on the rollers 17 so as to bring every part of the article under the action of the rotary brush 18. When sufficiently cleaned by the action 30 of the brush the foot is removed from the treadle 9 whereupon the platform or frame 13 and work table 16 at once drop so that the article can be removed from the work table, another article placed thereon, and the operation repeated.

In the case of washing the collars and cuffs of shirts, for example, the body of the shirt may hang down in the tank 1 and the collar or cuff portion thereof be laid over 45 the guide rail gutter 44 on to the work table. In drawing the shirt or the like out of the tank 1 over the front edge thereof when the washing operation is completed the gutter 42 receives the water dropping from the 50 wet shirt or the like and leads it back to the tank 1.

The rotary brush 18 is so mounted on the spindle 23 as to be readily removable so that when the bristles have become set in an inclined position by use and continued rotation in one direction the brush may be readily reversed in position on its spindle 55 in order to lengthen its life.

The brush spindle 23 is extended rearwardly as shown for convenience in cases where a motor drive is desired in place of a belt drive.

It will be appreciated that the improved machine is simple to operate and is particularly suitable for washing soft linen

collars, cuffs and like articles very quickly, efficiently, and with a minimum of labour.

As before stated the details of construction may vary without departure from the invention.

70

What I claim is:—

1. A laundry machine for washing collars, cuffs, and the like, comprising a rotary brush, a work-supporting table mounted to slide horizontally to and fro below said brush, means for delivering a cleansing solution to said brush, means normally pressing said work table downwardly away from said brush, and means for raising said work table against the action of said downwardly-pressing means to maintain the articles to be cleaned in contact with the brush. 75

2. A laundry machine for washing collars, cuffs and the like, comprising a rotary brush, a work-supporting table mounted to slide horizontally to and fro below said brush, means for delivering a cleansing solution to said brush, springs normally pressing said work table downwardly away from said brush, means for adjusting the pressure 90 of said springs, and means for raising said work table against the action of said springs to maintain the articles to be cleaned in contact with the brush.

3. A laundry machine for washing collars, cuffs and the like, comprising a rotary brush, a work supporting table mounted to slide horizontally to and fro below said brush, means normally pressing said work table downwardly away from said brush, 100 means for raising said work table against the action of said downwardly-pressing means, a cleansing liquid tank over which said rotary brush and said sliding work table are located, and a pump and conduits 105 to withdraw cleansing fluid from the said tank and delivered the same to the rotary brush.

4. A laundry machine as claimed in claim 1, comprising a fixed hood under which 110 said rotary brush is located and a funnel carried by said hood and through which cleansing liquid is delivered to said brush.

5. A laundry machine for washing collars, cuffs and the like, comprising a rotary brush, means for delivering a cleansing liquid to said brush, a work-supporting table, guides within which said table can slide horizontally to and fro below said brush, a structure to which said guides are fixed, 115 springs that constantly tend to maintain said structure in a lowered position away from said brush, a treadle lever, and mechanism connecting said treadle lever to said structure so that by depressing said lever the 120 said structure is raised towards said brush against the action of said springs.

6. A laundry machine for washing collars, cuffs and the like comprising a tank adapted to contain cleansing liquid, a sup- 125

port fixed over said tank and comprising vertically extending cylindrical pockets, a structure comprising guideways and having downwardly extending screwed rods that extend through the said cylindrical pockets, helical springs mounted on said rods within said pockets, nuts on said rods whereby the tension of said springs can be adjusted, slides mounted to reciprocate in said guideways, a work table carried by said slides, a brush mounted to rotate above said work table, a gland at the bottom of said tank, a rod extending vertically through said gland, the upper end of said rod being pivoted to said structure, a pedal located below said tank and to one end of which the lower end of said rod is connected, and a pump adapted to draw cleansing liquid from said tank and deliver the same to said rotary brush.

7. A laundry washing machine as claimed in claim 6 comprising a fixed hood under which the said rotary brush is arranged and funnels carried by said hood adapted to deliver cleansing liquid on to said brush.

8. A laundry washing machine as claimed in claim 6 comprising a splash gutter fixed to the front upper edge of the said tank and a pipe through which liquid collecting in said splash gutter can flow back into said tank.

In testimony whereof I affix my signature.
CHARLES BURROWS.
